UNITED STATES PATENT OFFICE.

HERBERT B. ANDREWS, WILLIAM H. HART, AND HOWARD B. SHERMAN, OF BATTLE CREEK, MICHIGAN, ASSIGNEES TO H. B. SHERMAN MANUFACTURING COMPANY, OF BATTLE CREEK, MICHIGAN, A CORPORATION OF MICHIGAN.

GROUND-CLAMP.

1,241,898.

Specification of Letters Patent.

Patented Oct. 2, 1917.

Application filed May 31, 1916. Serial No. 100,897.

To all whom it may concern:

Be it known that we, HERBERT B. ANDREWS, WILLIAM H. HART, and HOWARD B. SHERMAN, citizens of the United States, residing at Battle Creek, in the county of Calhoun and State of Michigan, have invented certain new and useful Improvements in Ground-Clamps; and we hereby declare that the following is a full, clear, and exact 10 description thereof, reference being had to the accompanying drawings, which form part of this specification.

This invention is a novel improvement in ground clamps and our object is to produce 15 a clamp that can be made of soft metal such as copper and will be strengthened at the point where the bolt head is applied so that such head will not tear the clamp; and which will have a holder or socket for engagement with the end of a wire; and whereby tipping of the ends of the clamp together, before it is properly tightened around the object to which it is applied, will be prevented; and which clamp can be readily applied to an object such as a rod or pipe.

The invention consists in the novel construction of the clamp as hereinafter described and illustrated in the accompanying drawings, and the essential features of construction for which protection is desired are 30 summarized in the claims.

In said drawings:

Figure 1 is a perspective view of our ground clamp as applied to a pipe, and 35 showing a wire connected therewith.

Fig. 2 is an enlarged vertical sectional view through the ears of the clamp in the plane of the bolt.

Fig. 3 is a similar sectional view through 40 the socket portion of the clamp.

Fig. 4 is a transverse or horizontal section through the clamp in the plane of the bolt.

Fig. 5 is an inside view of the countersunk ear of the clamp.

Fig. 6 is a reverse view of Fig. 5.

Our ground clamp, as shown, comprises a body preferably made of a strip of soft metal, such as copper, which is a good conductor of electricity. This body can be bent 50 as shown to facilitate its application to a pipe, rod or object to which the clamp is to be applied; and one end of this body forms an ear 1 in which is an opening 1^a for the passage of a securing bolt 2. Partially sur-

rounding this opening 1^a on the exterior of 55 the ear is a recess or counter-sink 1^b (Fig. 6), preferably produced by stamping the metal, and when so produced forming a projection 1^c on the inside of the ear (Fig. 5). The said countersunk portion is inclined to the 60 body of the ear so as to give the head of the bolt a full bearing against such ear, as indicated in Fig. 4. The edge of the opening 1^a within this recess is preferably flanged 65 as at 1^d.

Said recess or counter-sink 1^b helps to stiffen the metal around the bolt head, where the strain ordinarily first comes, and where tearing would ordinarily begin; and said counter-sink also provides a place where a 70 small wire might be secured beneath the head 2^a of the screw 2, in case it was desired to attach a wire to the clamp at this point.

The head of the bolt 2 would be apt to cut or burst through the opening in the ear, 75 when the clamp was applied to an object and the bolt 2 tightened; but the counter-sink 1^b prevents such tearing through, and it provides a large flat bearing for the inner edge of the bolt head. The flange 1^d around 80 the edge of the opening 1^a also greatly reinforces and strengthens same and prevents the bolt tearing out or enlarging the opening.

At the outer end of this ear 1 the extremity of the body is bent upon itself to form a loop or socket, in which socket is preferably secured a cartridge or thimble 3 (Figs. 3 and 4) closed at one end and open at the other end. Said thimble may be formed by 85 drawing a suitable metal shell to fit into the loop, and such shell can be readily secured in the loop by dipping same in molten tin or solder. Said shell is adapted to hold 90 solder, and when the clamp is applied to a rod or pipe so that the shell or socket is in a vertical position (as in Figs. 1 and 3) the closed end of the socket should be at the bottom so that hot solder can be placed in 95 the socket, or the socket heated to melt the solder, and the end of a wire W can be inserted in the socket as indicated in (Figs. 1, 3 and 4) and be securely fastened thereto, or the end of a wire can be coated with tin or solder and inserted into the socket to solder the wire in place. The closed end of the shell prevents the hot solder dropping 100 out of the socket when the same is hot, and

when the end of the wire is inserted therein. If the shell were not used and it was attempted to heat solder in the looped end, or to place hot solder therein, the solder would 5 run out of the end of the loop, and it would be difficult to close up one end of the loop sufficiently to hold the solder, as hot solder will run out of joints which would hold water.

- 10 Preferably a flat brass washer 4 is placed on the bolt between the head 2^a and the ear. Such washer fits in the counter-sink 1^b as shown and decreases the friction of the bolt head on the metal, and gives additional security 15 against possibility of the bolt head digging into or cutting the metal. Such washer also assists in preventing improper tipping or bending the ears out of shape when the clamp is fastened to a rod or pipe.
- 20 The clamp body may be provided with a series of perforations 1^c adjacent its other end, with one of which perforations the bolt 2 is engaged when the clamp is applied to a rod or pipe. The nut 2^c on the bolt engages 25 the end of the clamp opposite the ear 1 as shown; and enables the clamp to be very easily and firmly secured to an object.

The looped end 1^e of the ear 1 also performs the function of preventing the ears or ends of 30 the clamp tipping together too quickly, and spaces the outer ends of the ears apart, and thus enables the bolt 2 to tightly secure the clamp to the object. The looped end of the clamp insures that the clamping strain on 35 the bolt and nut will be equally distributed at the bottom or inner ends of the ears as well as the top or outer ends thereof, and thus insures that the body of the clamp gets a larger and better surface contact with the 40 rod or pipe to which it is applied.

The washer 4 not only prevents the head of the bolt digging into the metal, but it also serves as a convenient means to enable a wire to be fastened around the bolt beneath the 45 head and between the washer and the bottom of the counter-sink or body of the ear.

With such ground clamps electric connections can be made either by soldering the end of the wire in the socket or looped end of 50 the body; or by bending the end of a wire around the bolt between the brass washer and the ear. In the latter case the depression or counter-sink in the ear forms an excellent retainer for the end of the wire.

55 In constructing the clamps, instead of punching the bolt opening in the counter-sink full size, we prefer to make it small and then enlarge it by turning down its edge to form the flange 1^d; and by thus flanging

the metal around the bolt opening the copper 60 is reinforced at the weakest point, and the clamp bolt can be applied very tightly without tearing the opening; or the head of the bolt bursting through the opening.

The principal essential and novel features 65 of our ground clamp are, the looped or socketed end, the depression or counter-sink for the head of the bolt, the flange around the opening beneath the bolt head, the shell in the looped end, and the washer engaging the 70 bolt and fitted within the counter-sink or depression.

What we desire to protect is set forth in the following claims.

1. A ground clamp formed of a strip of 75 suitable metal, and provided at one end with a loop, and a shell in said loop closed at one end.

2. A ground clamp formed of a strip of 80 suitable metal, having a stamped counter-sunk portion with an opening for the engagement of the head of a bolt, the said countersunk portion being inclined to give the head of the bolt a full bearing against the ear; and the edge of said opening being 85 flanged to reinforce same.

3. A ground clamp formed of a strip of 90 suitable metal, having a stamped counter-sunk portion with an opening in said portion for the engagement of the head of a bolt, the said countersunk portion being inclined to give the head of the bolt a full bearing 95 against the ear.

4. A ground clamp formed of a strip of 95 suitable metal, provided at one end with a loop for the engagement of a wire, a counter-sink adjacent said loop, and a bolt opening in the counter-sink, the edge of said opening being flanged.

5. A ground clamp formed of a strip of 100 suitable metal, provided at one end with a socket for the engagement of a wire closed at one end, and a counter-sink adjacent said socket having an opening for the passage of a bolt.

6. A ground clamp formed of a strip of 105 suitable metal, provided at one end with a loop for the engagement of a wire, and an inclined counter-sink adjacent said loop having an opening for the passage of a bolt; 110 with a bolt and a washer thereon adapted to engage the counter-sink.

In testimony that we claim the foregoing as our own, we affix our signatures.

HERBERT B. ANDREWS.
WILLIAM H. HART.
HOWARD B. SHERMAN.
